HANGER SYSTEM FOR FLEXIBLE HANGINGS

Annette E. Fridolph, New York, N. Y.

Application October 14, 1954, Serial No. 462,182

3 Claims. (Cl. 16—95)

This invention relates to a hanger system for supporting hangings of cloth or other flexible fabrics such as curtains, draperies or the like. The invention particularly relates to a unitary member which serves as a traverse member for slidably supporting curtains, draperies and the like.

This invention may be considered as an improvement over the arrangement shown in my prior patent Re. 23,209. In said patent, there is shown a traverse member for draperies and the like in the form of a unitary member provided with a T slot. Within the slot, a plurality of sliders are longitudinally movable. Curtains, draperies or the like are attached to fabric tabs depending from the sliders through the portion of the slot which opens on one face of the traverse member. In the case of the traverse member through which the slot opens, there is provided a recess through which the sliders may be passed for inserting them into the groove and for their removal from the groove. Under normal conditions, the sliders slide along the slot in the traverse member past the recess. They must be manipulated in a special manner; that is, tilted angularly downwardly at one end to move them through the recess. Experience has shown that when a drapery suspended in the manner illustrated in said prior patent is pulled along the traverse member with a considerable downward force, the slider members sometimes become cocked as they pass by the recess and accidentally move through the recess.

It is an object of this invention to provide a hanger construction for curtains, draperies and the like generally of the type disclosed in said prior patent and designed to permit easy insertion and removal of the slider members into and from the T-shaped slot of the traverse member.

A further object of the invention resides in the provision of a traverse member in this type of arrangement having an opening or recess therein for insertion and removal of the slider members, the recess being so designed that it does not interfere with the sliding movement of the sliders past the recess even if the drapery or curtain is very heavy or if the slider is being pulled along the slot with a considerable downward force.

In the drawings:

Fig. 1 is a side elevation of the traverse member of this invention showing sliders therein supporting a drapery or the like.

Fig. 2 is an end view of the arrangement shown in Fig. 1.

Fig. 3 is a bottom plan view of a portion of the traverse member.

Fig. 4 is a perspective view of the slider member attached to a drapery or the like.

Fig. 5 is a perspective view showing the manner in which the slider members are inserted into or removed from within the groove of the traverse member.

Fig. 6 is a bottom plan view of the traverse member illustrating the manner in which the slider member is inserted into or removed from within the groove in the traverse member.

2

Referring to the drawings, the traverse member of the present invention which is generally designated 10 comprises a one piece track which may be formed of wood or metal as desired. In the particular construction shown, 5 the traverse member 10 is illustrated as an extrusion formed of aluminum or the like. At the top side thereof, the member 10 is provided with a pair of attaching flanges 12. A pair of side walls 14 depend from the flanges 12; and at its lower end, the member 10 is provided with a 10 bottom wall 16. Between the walls 14, the track is provided with a T-shaped groove 18 which defines a slot 20 in the bottom wall 16.

The slider members of the present invention, generally designated 21 may be generally the same as disclosed in 15 my prior patent referred to. These slider members are preferably formed from cloth or tape and are fashioned with an enlarged head 22 and a depending tab 24. The enlarged head 22 preferably includes a rigid reinforcing member 26 around which the fabric is sewed or otherwise 20 secured to form the head 22. However, the sliders may be made wholly of a single material such as fabric rolled or stitched to form the head, or may be fashioned from materials such as metal, wood or plastic. A plurality of sliders 21 may be sewed at regularly spaced points to a 25 cloth tape which is in turn sewed to the upper edge of a drapery or curtain; or if desired, the tabs 24 may themselves be sewed at regularly spaced points to the upper edge of a curtain or drapery. The head 22 of slider 21 is dimensioned to have a nice sliding fit in the groove 30 30 with the tabs 24 depending through the slot 20 as illustrated in Fig. 2. This construction provides a noiseless and smoothly running traverse drapery arrangement; and since the sliders have but little friction with the groove 18, the sliders 21 together with the curtain or drapery 28 are 35 very freely movable along the traverse member 10. The member 10 may be fitted neatly within a door or window opening and concealed, if desired, in any suitable manner. At each end, the member 10 is provided with rivets 30 or the like which extend across groove 18 and thereby 40 prevent the sliders 21 from sliding out either end of member 10.

It is, of course, necessary to provide some form of means for enabling the sliders 21 to be removed from 45 within groove 18 so that the curtain or drapery may be taken down and rehung without detaching it from the tabs 24. Accordingly, in one of the side walls 14 of the member 10, there is formed an elongated opening 32. Opening 32 communicates at its inner end with groove 18 and is spaced above the plane of bottom wall 16. A slot 34 extends from one end of opening 32 through walls 14 and 16 to slot 20. Slot 34 is inclined at an acute angle to the plane of wall 16 and has a width which generally corresponds to the width of slot 20. The width of opening 32 corresponds generally with the width of the heads 55 22 of sliders 21. However, opening 32 is shorter in length than the heads 22 of sliders 21. It will be noted that at the junction between opening 32 and slot 34, slot 34 tapers to a slightly greater width with the side edges of the slot blending smoothly with the edges of opening 32 at one end thereof as indicated at 36 and 38.

With the arrangement described herein, it will be observed that since the lower edge 40 of opening 32 is disposed above the upper face of bottom wall 16, the sliders 21 will normally slide freely past opening 32. However, 65 if the drapery is pulled to the right as viewed in Fig. 1 and in a lateral direction from the side of member 10 on which the opening 32 is located, then as each slider 21 approaches opening 32, the tab 24 will tend to ride up into slot 34. As the tab 24 rides up through slot 34, the head 22 of the slider is caused to be turned through approximately 90° as illustrated in Figs. 5 and 6. Thus, as 70 the pull on the slider is continued in a direction laterally

away from the side wall 14 in which the opening 34 is formed, the leading end of the slider will be guided through opening 32 in a position inclined to the plane of wall 32. Thus, when the drapery is so pulled, each slider will be moved through the opening 32 as the tab 24 of each slider rides up through the slot 34.

The operation of hanging the drape or curtain is performed just as easily and quickly as the operation of removing the drape. To hang the drape, it is necessary to insert each of the sliders 21 through the opening 32. This is accomplished very simply by inserting the head 22 of each slider angularly through opening 32 and at the same time directing tab 24 into the slot 34. The smooth tapered edges indicated at 36 and 38 insure the free sliding movement of heads 22 and tabs 24 through opening 32 and slot 34 respectively.

Thus, it will be seen that I have provided a hanger construction for curtains, draperies and the like, which is of simple construction and which enables the drapery or the like to be moved along the traverse member quietly and freely. The invention also provides a traverse arrangement which eliminates the possibility of accidental removal from within the groove when the drapery is pulled along the traverse member but which, at the same time, enables the slider members to be readily and easily inserted or removed from within the groove of the traverse member.

I claim:

1. A track for supporting curtains, draperies and the like by means of sliders movable in a longitudinally extending groove formed in the bottom face of the track, with drapery supporting tabs on the sliders extending through the groove characterized in that the groove has

5 a narrow portion and an enlarged portion with the narrow portion of the groove disposed adjacent the bottom face of the track, the track having a side face extending longitudinally adjacent the groove, said side face having an aperture therethrough opening at its inner end in the enlarged portion of said groove, said bottom and side faces having a slot therein extending therethrough from the narrow portion of the groove to said aperture, said slot lying in a plane normal to the side face of the track and inclined at an acute angle, to the axis of the groove, whereby when a drapery is supported in said track as described and a pull exerted thereon in a direction longitudinally of the track and at an angle inclined to the plane of said side face, the tabs on the sliders automatically travel into said slot and the sliders pass out of said groove through said aperture.

2. A track for supporting curtains, draperies and the like as called for in claim 1 wherein said aperture is elongated in a direction longitudinally of said track, said slot terminating at one end of said aperture and said aperture forming a longitudinal extension of said slot, the width of said aperture being greater than the width of said slot.

3. A track for supporting curtains, draperies and the like as called for in claim 2 wherein the intersection of said slot and said aperture is defined by arcuate edges forming smoothly flowing lines connecting the slot and aperture.
